2 SHEETS—SHEET 2.

UNITED STATES PATENT OFFICE.

GEORGE W. WEISS, OF NEW YORK, N. Y.

MACHINE FOR MAKING HAT-LININGS.

1,347,001.

Specification of Letters Patent. Patented July 20, 1920.

Application filed December 31, 1917. Serial No. 209,724.

To all whom it may concern:

Be it known that I, GEORGE W. WEISS, a citizen of the United States, and resident of New York city, in the county of New York and State of New York, have invented certain new and useful Improvements in Machines for Making Hat-Linings, of which the following is a full, clear, and exact description.

10 The invention relates to machines for making hat linings in which the lining is supported on a turn table that has an oval movement and in which said turn table is moved toward a cutter to trim off the surplus material after which it is brought back to its original position in line with a sewing machine to sew a side lining of silk or other material around the edge of the lining proper, and has for its object the simultaneous mechanical control of the mechanism that controls the size and shape of the linings. A further object of this invention is to provide means for simultaneously locking in adjusted position the mechanism that controls the size 25 and shape of the linings. Particularly this invention contemplates improvements on the hat lining machine of Henry Charmbury patented Dec. 18, 1894 Serial Number 531,098. The Charmbury machine has a bed 30 plate upon which is mounted by means of a bolt at one end a carriage which may be oscillated back and forth from cutting to sewing position. Upon this carriage is mounted the mechanism for controlling the size and shape of the lining. The shape is 35 controlled by the upper slide bar and the size by the lower slide bar. Each slide bar is positively locked by a separate screw. This invention utilizes the oscillatable carriage of 40 Charmbury but provides means for actuating the slide bars and also varies the structure of these slide bars. In the preferred form two rotatable cam plates move the slide bars in one direction and springs keep 45 the bars in contact with the cams. One set screw positively clamps both bars in adjusted position. Auxiliary means are also provided on both slide bars permitting a supplemental adjustment of the length of each 50 slide bar whereby odd sizes and shapes may be produced. The invention involves various features which will be described more fully hereafter and particularly pointed out in the claims. Reference is to be had to the 55 accompanying drawings in which similar

characters of reference indicate corresponding parts in all figures:—

Figure 1 is a plan view showing the relation of the sewing machine, the cutter and the oval mechanism. 60

Fig. 2 is a plan view of the support for turn table and the controlling cams.

Fig. 3 is a front view of Fig. 2 with parts in section.

Fig. 4 is a rear view of Fig. 3. 65

Fig. 5 is a sectional view of the turn table mechanism on line 5—5 of Fig. 2.

Fig. 6 is a sectional view on line 6—6 of Fig. 2.

Fig. 7 is a sectional view on line 7—7 of Fig. 5. 70

Fig. 8 is a view of cutter disks.

In the annexed drawings I have shown a plan view of the cutter mechanism A and sewing machine B to show their relation to the oval mechanism and to each other. Fig. 8 shows how the cutter disks coact with each other to cut. These are part of the usual cutting mechanism used on machines of this character, and being no part of the invention are not particularly referred to. 80

In the construction of my improved machine I provide a base plate 1 which is secured to the table 2 by means of the screw stud 3 so that it is free to swing forward to the cutter A. On base plate 1 is supported a slide bar 4 which is secured to base plate 1 by thumb bolt or screw 5 which passes through a slot on base plate 1 into a recess on the under side of base plate 1 where it is fastened with a nut as shown in dotted lines in Fig. 3. On slide bar 4 is supported another slide 6 which is secured to bar 4 by screws 7—7 going through slots in slide 6 and screwing into slide 4. These screws are 95 to be set so that slide 6 has a back and forward movement on slide bar 4. Slide 6 is provided with two raised portions 8—8 upon which is supported a slide 9 which is held in place by thumb screw 10 and screw 11. Slide 9 is slotted so that it may be moved in and out. On slide 9 is secured a bent piece 12 which is adapted to come in contact with and engage socket or cork holder 21 on oval plate 19, and slide 9, to which piece 12 is secured, is clamped in position with thumb screw 10. On the end of slide bar 4 is a projection 13 upon which is supported a circular disk 14. On this disk the turn table 15 which consists of a plate with two down- 100

105

110

wardly projecting edges which fit over the disk 14 revolves. In disk 14 is a slot 14^a shown in Fig. 7. A pin 17 is secured to slide 6. When turn table revolves around disk 14 the pin 17 moves back and forth in the slot 16, which imparts an oval movement to the turn table. By moving the slide 7 with pin 17 in or out it changes the shape of the oval movement. In turn table 15 is a slot 16 shown in Fig. 7. Pin 17 is secured to slide 6. When slide 6 is moved in or out the pin 17 will move in or out of slot 14^a in disk 14. This makes the oval wide or narrow. Secured to the turn table 15 are two projections 18. On these projections is secured the oval plate 19 by screws 20. Made integral with oval plate 19 are four sockets 21 which contain corks or any other material of a like nature. Arranged above oval plate 19 is another oval plate 22 which is provided with four projections 21^a to support needles 24^a fastened with screws 23 or otherwise secured. The lining 22^a is clamped between 19 and 22 as shown in Figs. 3-4-5. In the center of oval plate 19 is also a projection which contains a needle 24. To oval plate 22 is secured a handle part 25. A spring 26 is secured to base plate 1 and slide bar 4. Spring 27 is secured to slide bar 4 and slide 6. These springs serve to keep slide bar 4 and slide 6 against the cams as will be hereinafter described. A hand lever 28 is secured to base 1 by screw 29 and held down by spring 30. A recess 31 in table is adapted to receive the end of lever 28 and keep base 1 in position to prevent it from moving while the lining is being stitched. On screw stud 3 which fastens base 1 to table 2 I support two cams 32 and 33 as shown in Fig. 6. These cams are fastened together so that they turn in unison. A set screw 32^a is mounted in the bearing of the cam 32, which is rotatably mounted on the bearing of cam 33, so that when the screw is tightened cams 32 and 33 rotate together on the stud 3. When the set screw 32^a is loosened the cam surfaces may be relatively adjusted so that a surface of different outline may be presented to the slide 4 from that presented to slide 6. They have cam faces 34 each one of which is at a lesser distance from the center than the one preceding it as shown in Fig. 2. These cams are for the purpose of controlling the slide bar 4 and slide 6 to make linings to fit all size hats. Cam 32 controls slide 6 which changes the shape of the oval and cam 33 controls slide bar 4 which controls the size of the oval. In the preferred form the curvature or outline of cam 33 varies slightly from that of cam 32. This is clearly shown in plan in Fig. 2. The shape of human heads varies, as well as the size. A standard mean for a particular clientele may however be gaged by observation so that the shape of

the cam that effects change in shape of the oval can be adapted to the need or experience of a manufacturer. This eliminates the necessity of adjusting one cam with reference to the other. The cam disk 32 has holes 35 into which a plunger 36 fits. The plunger 36 is supported in a bearing on angle piece 44 that is secured to a plate 37 by screws 38. Plate 37 is secured to base 1. A collar 39 is fastened to screw stud 3 on top of cams 32 and 33 to hold them in position. Two slides 40 and 41 are secured to slide bar 4 and slide 6 with screws 42. Slides 40 and 41 have slots 43 which permit them to be set in or out to change the position of slide bar 4 and slide 6 in relation to cams 32-33. The cams 32 and 33 bear directly against slides 40 and 41 as shown in Fig. 2. To the cam disk 32 is fastened a dial plate 45 which has the sizes of the different hats marked on it which, in conjunction with the plunger 36 enables one to set the cams to make linings of any size without any measuring, marking or other adjustment. The number of the size linings one wishes to make must be opposite the end of slides 4 and 6 and not opposite the plunger 36. The cams 32 and 33 adjust the oval device so that the linings will fit the size hat for which it was made. After the size of the lining you wish to make has been set, the slides are fastened to base 1 by tightening thumb screw 5 which locks slide bar 4 and slide 6 to base 1 and prevents any change in the size which might be caused by the accidental shifting of the slides. On table 2 a stop 46 is secured which limits the forward movement of base 1 when it is moved toward the cutters. The operation of my improved machine is as follows:—Raise the plunger 36 so that it clears the cam 32, turn cam 32 so that the cam face producing the size you wish to make will be opposite and bearing on the slide 40 as shown in Fig. 2. Then let plunger drop into hole 35. This locks the cams in position and prevents any accidental displacement of them. Tighten thumb screw 5. Turn oval attachment until the socket with the cork in one of the long ends in oval plate 19 is in line with slide 9. Move slide 9 until part 12 comes in contact with socket 21 that holds the cork and tighten thumb screw 10. This locks the oval plate straight while the lining is being put on. Take off oval plate 22, place the lining with its center over the needle point 24 on oval plate 19, put back oval plate 22, so that the needles will go through the lining into the corks in the sockets in oval plate 19. Press oval plate 22 down tight, which confines the lining between the plates 22 and 19. Push back slide 9 so that part 12 moves away from cork socket on oval plate, thus allowing turn table to move easily and without resistance. Press down lever 28

so that the end that fits into table 2 will be clear, push base 1 toward the cutter B until it reaches stop 46 on table. Then cut the lining all the way around by turning the 5 turn table with the lining on until the entire edge of lining has been trimmed off. Bring back the base 1 until lever 28 slips into the hole in the table and locks it in position. Then stitch the lining around the 10 edge with the sewing machine. By means of the cams 32 and 33 and the plunger 36 quick, positive and accurate adjustments of both the size and shape of the lining are made so that an inexperienced person may make 15 them in an instant. If an independent adjustment of either the size or shape of lining is desired it can be done by adjusting the auxiliary slides 40 and 41 as may be necessary. I do not wish to limit myself to the 20 particular construction shown and described as various modifications and changes may be made without departing from the spirit of the invention.

What I claim as new and desire to secure 25 by Letters Patent is:—

1. In a machine for cutting hat linings, means for supporting the material to be cut comprising a structure mounted to turn in a horizontal plane so that a predetermined 30 fixed point in said plane describes a predetermined curve of oval form on said structure, a mounting for said structure, adjustable means for changing the size of said curve, adjustable means for changing the 35 shape of said curve, and means for simultaneously setting said adjustable means in predetermined position.

2. In a machine for cutting hat linings, means for supporting the material to be cut 40 comprising a structure mounted to turn in a horizontal plane so that a predetermined fixed point in said plane describes a predetermined curve of oval form on said structure, a mounting for said structure, a slide 45 for changing the size of said curve, a second slide for changing the shape of said curve, and means for simultaneously setting said slides in predetermined position.

3. In a machine for cutting hat linings, 50 means for supporting the material to be cut comprising a structure mounted to turn in a horizontal plane so that a predetermined fixed point in said plane describes a predetermined curve of oval form on said structure, a mounting for said structure, a spring-retracted slide for changing the size of said curve, a second spring-retracted slide for 55 changing the shape of said curve, and means for simultaneously setting said slides in predetermined position.

4. In a machine for cutting hat linings, 60 means for supporting the material to be cut comprising a structure mounted to turn in a horizontal plane so that a predetermined fixed point in said plane describes a prede-

termined curve of oval form on said structure, a mounting for said structure, a spring-retracted slide for changing the size of said curve, a second spring-retracted slide for changing the shape of said curve, and two 70 cams mounted for simultaneous movement on the same axis, one adapted to engage the end of one slide and the other the end of the other slide.

5. In a machine for cutting hat linings, 75 means for supporting the material to be cut comprising a structure mounted to turn in a horizontal plane so that a predetermined fixed point in said plane describes a predetermined curve of oval form on said structure, a mounting for said structure, a slide for changing the size of said curve, a second slide for changing the shape of the curve, means mounted on each slide whereby the length of said slide may be varied, and cams 80 adapted to simultaneously actuate said slides.

6. In a machine for cutting hat linings, 90 means for supporting the material to be cut comprising a structure mounted to turn in a horizontal plane so that a predetermined fixed point in said plane describes a predetermined curve of oval form on said structure, a mounting for said structure, a spring-retracted slide for changing the size of said 95 curve, a second spring-retracted slide for changing the shape of said curve, and means for simultaneously actuating said slides, comprising two cams mounted to turn on the same axis, means for securing said cams 100 against relative movement, and means for locking one of said cams against turning.

7. In a machine for cutting hat linings, 105 means for supporting the material to be cut comprising a structure mounted to turn in a horizontal plane so that a predetermined fixed point in said plane describes a predetermined curve of oval form on said structure, a mounting for said structure, a spring-retracted slide for changing the size of said 110 curve, a second spring-retracted slide for changing the shape of said curve, and means for simultaneously locking said slides against movement.

8. In a machine for cutting hat linings, 115 means for supporting the material to be cut comprising a structure mounted to turn in a horizontal plane so that a predetermined fixed point in said plane describes a predetermined curve of oval form on said structure, a mounting for said structure, a spring-retracted slide for changing the size of said curve, a second spring-retracted slide for 120 changing the shape of said curve, means for simultaneously setting said slides in predetermined position, and means for simultaneously locking said slides in said position.

9. In a machine for cutting hat linings, 125 means for supporting the material to be cut comprising a structure mounted to turn in a 130

horizontal plane so that a predetermined fixed point in said plane describes a predetermined curve of oval form on said structure, a mounting for said structure, adjustable means for changing the size of said curve, adjustable means for changing the shape of said curve, and means for simultaneously setting said adjustable means in predetermined position, said last-mentioned means comprising two cams having surfaces of different shape adapted to rotate on the same axis.

10. In a machine for making hat linings, the combination with a device for producing oval rotation, means for supporting the lining on said oval producing device, slides for changing the size and shape of the oval, controlling means acting simultaneously on the slides, and means for locking said controlling means, substantially as shown and described.

11. In a machine for making hat linings, the combination with a device for producing oval rotation; means for supporting the lining on said oval producing device; a swinging support for said oval producing device; compound controlling devices operating simultaneously; a locking device supported by said swinging oval support for locking said controlling devices and swinging oval support together in different positions; substantially as shown and described.

12. In a machine for making hat linings the combination with a device for producing oval rotation; means for supporting the lining on said oval producing device, means for locking said oval device against rotation, primary controlling devices, means for locking said controlling devices, and secondary controlling devices, located between said primary controlling devices and the oval turning device substantially as shown and described.

13. In a machine of the class described the combination with a device for producing oval rotation, means for supporting the hat lining on said oval producing device, slides for changing the size and shape of the oval, means as shown and described for simultaneously controlling the movements of the slides, means for locking said controlling means, and secondary controlling devices located between said simultaneous controlling means and the oval rotation producing device.

14. In a machine of the class described the combination with a swinging base, a device for producing oval rotation supported on said swinging base, means for supporting the hat lining on said oval producing device, slides for changing the size and shape of the oval, rotary members for simultaneously controlling said slides, and locking means supported by the swinging base for locking

said rotary members substantially as shown and described.

15. In a machine for making hat linings, the combination with a swinging base, a device for producing oval rotation supported on said swinging base, means for locking said base in its operative position, means for supporting the hat lining on the oval producing device, means for intermittently locking said oval device against rotation, slides for controlling the size and shape of the oval, adjusting devices carried by said slides, means for securing said adjusting devices in their adjusted positions, means for simultaneously controlling the movement of the slides, and means carried by the swinging arm for locking said simultaneously controlling means in definite positions substantially as shown and described.

16. In a machine for making hat linings, the combination with a cutter, a device for producing oval rotation supported for movement to and from said cutter, means for supporting the lining on said oval producing device, locking means for securing said oval producing device in fixed relation to the sewing machine, slides for changing the size and shape of the oval, cams for simultaneously controlling the movement of the slides, means for locking the cams against movement, means carried by the slides for independently adjusting them in relation to the cams, and means for intermittently locking said oval against rotation.

17. In a machine for making hat linings, the combination with a swinging base, a device for producing oval rotation supported on said swinging base, of means for locking said base in its operative position, means for supporting the hat lining on said oval producing device, a slide for changing the shape of the oval, a slide for changing the size of the oval, cams for simultaneously controlling the movement of the slides, a dial on the cams, means carried by the base for locking the cams against movement, means for locking the slides to the base, and means for intermittently locking said oval against rotation substantially as shown and described.

18. In a machine for making hat linings the combination with a swinging base, a device for producing oval rotation supported on said swinging base, means for locking said base in its operative position, means carried by said oval producing device for supporting a hat lining, means for intermittently locking said oval producing device against rotation, slides carried by the base for changing the size and shape of the oval, means for locking said slides to the base, means for simultaneously controlling the slides, a dial for indicating the sizes of the linings carried by said controlling means, means for locking said controlling means in different positions, means carried by the

slides for independently regulating their relation to the controlling means, and means for securing said independent regulating devices in their adjusted positions substantially as shown and described.

19. In a machine for making hat linings the combination with a swinging base, a device for producing oval rotation supported on said swinging base, a stud for pivotally securing said base to the table, means for locking said base in its operative position, slides carried by the base for changing the size and shape of the oval, means supported by the stud for simultaneously controlling the movement of the slides, means for locking the slides to the base, a locking device carried by the base for locking said controlling means in different positions, a dial secured to the controlling means for indicating the sizes to be made, means for supporting a hat lining on the oval producing device in proper relation to a sewing machine and cutters, and means for intermittently locking said oval producing device against rotation substantially as shown and described.
20. In a machine for making hat linings the combination with a swinging base, a device for producing oval rotation carried by

said swinging base; a stud for pivotally securing said base to the table; means for locking said base in its operative position; slides carried by the base for changing the size and shape of the ovals; means supported by the stud for simultaneously controlling the movement of the slides in one direction; springs for controlling the movement of the slides in the opposite direction; means for locking the slides to the base in their adjusted positions; a locking device carried by the base for locking said controlling means in different positions; a dial secured to the controlling means for indicating the sizes to be made; means for supporting a hat lining on said oval producing device in proper relation to a sewing machine and cutters; and means for intermittently locking said oval device against rotation; substantially as shown and described.

Signed at New York city, in the county of New York and State of New York this 19th day of December, A. D. 1917.

GEORGE W. WEISS.
